CLOSURE FASTENER

Elmer J. Zelt, Fort Wayne, Ind., assignor to General Electric Company, a corporation of New York

Application September 29, 1950, Serial No. 187,482

2 Claims. (Cl. 220—60)

1

This invention relates to closure fasteners and, more particularly, to improvements in cover fasteners for casings for small electrical devices, such as ballasts for fluorescent lamps.

Heretofore covers for casings of the above-mentioned type have been fastened in place by screws or rivets, thus requiring a separate fastening operation after the cover has been put in place over the opening in the main body portion of the casing.

In accordance with the present invention, there is provided a novel, simple and inexpensive snap fastener which automatically fastens the cover to the casing when the cover is pressed into place over the opening in the main body of the casing, thus entirely eliminating a separate cover fastening operation. In addition, the parts of the fastener are integral with the main parts of the casing and cover and are formed therein at the time those parts are formed. Usually, the casing parts are made of sheet steel and they are stamped automatically to the proper shape.

An object of the invention is to provide a new and improved closure fastener.

Another object of the invention is to provide a new and improved snap action closure fastener.

An additional object of the invention is to provide a new and improved cover fastener for the casing of a relatively small electrical device, such as a ballast for fluorescent lamps.

The invention will be better understood by considering the following description taken in connection with the accompanying drawing and its scope will be pointed out in the appended claims.

In the drawing, Fig. 1 is a side elevation of a casing embodying the present invention with a portion thereof shown broken away and in section.

Fig. 2 is an enlarged detailed perspective view for illustrating the operation of the fastener shown in Fig. 1. Fig. 3 is a view similar to Fig. 2 showing the parts locked or fastened together, and Fig. 4 is an end view taken on line 4—4 of Fig. 3.

Referring now to the drawing, and more particularly to Fig. 1, there is shown therein a casing consisting of a main tub-like body portion 1 and a flat cover member 2. The main portion is provided with a pair of outwardly extending oppositely disposed flat end flanges 3 which lie in the same plane and the cover 2 is provided with ends 4 which overlie the flanges 3. Part of each end 4 of the cover member 2 consists of an integral projection 5 which is bent at substantially right angles to the plane of the cover 2 toward

the main casing portion 1. These projections 5 fit into openings 6 provided in the end flanges 3 of the main casing portion 1.

As shown more clearly in Fig. 2, the projection 5 has a relatively long base 7 and a relatively short end 8 joined by tapering sides 9. In addition, there are notches 10 in the sides of the projection 5 adjacent to base 7.

The general shape of the openings 6 is similar to that of the projections 5 and consists of a long inner end 11, a short outer end 12, and tapering sides 13. The length of the short end 8 of the projections 5 corresponds generally to the length of the short outer ends 12 of the openings 6 and, likewise, the length of the base 7 of the projections 5 corresponds generally to the length of the inner long ends 11 of the openings 6.

The operation of the fastener is as follows. When the cover 2 is placed over the opening in the main tub-like portion 1 of the casing with the ends of the projections 5 entering the openings 6 as shown by the full line position of the projection 5 in Fig. 2, the tapering sides 9 of the projections 5 will engage the tapering sides 13 of the openings 6. If, now, pressure is applied forcing the cover down onto the flanges 3, the tapers of the projections 5 and the openings 6 will cause the projections to bend inwardly toward the main casing portion 1 as shown by the dashed line position of the projection 5 in Fig. 2. This action will continue until the shoulders of the notches 10 pass through the openings 6 whereupon the projections 5 will snap outwardly to the position shown in Figs. 1 and 3 whereby the notches 10 embrace the sides 13 of the openings 6 and securely lock the cover in place.

It will thus be seen that the fastening or locking action of the fastener takes place automatically in the assembly of the device, that is to say, when the cover 2 is pressed into place on the main body portion 1, and that no additional fastening operation is necessary.

If it is desired to remove the cover 2, it is only necessary to bend the ends of the projections 5 inwardly until the shoulders of the notches 10 clear the sides of the openings 6.

While there has been shown and described a particular embodiment of the invention, it will be obvious to those skilled in the art that changes and modifications may be made without departing from the invention, and that it is intended by the appended claims to cover all such changes and modifications as fall within the true spirit and scope of the invention.

What I claim as new and desire to secure by Letters Patent of the United States is:

1. In an electrical device casing of the type having a main tub-like portion with outwardly extending oppositely disposed flat end flanges in the same plane and a flat cover member having ends which overlie said flanges, complementary shaped interfitting openings and projections on said flanges and cover ends, said projections being integral portions of said cover ends which are bent at substantially right angles to the plane of said flat cover toward said flanges, said projections having at least one notch in their sides adjacent the surface of said cover, said openings and said projections being of tapering configuration and so spaced relative to each other that said notches embrace the edges of said recesses for locking said cover in place. 5 10 15

2. In an electrical ballast casing of the type having a main tub-like portion with outwardly extending oppositely disposed flat end flanges in

the same plane and a flat cover member having ends which overlie said flanges, an opening in each flange having a long inner end and a short outer end joined by straight tapered sides, an integral projection on each end of said cover extending substantially at right angles to the plane of said cover toward said main casing portion, each projection having a long base and a short end joined by straight tapered sides and notches in the sides of each projection adjacent its base, the length of the base of each projection being substantially equal to the long inner end of each flange opening, the short end of each projection being substantially equal to the length of the short outer end of each opening, said notches embracing the sides of said flange openings for fastening said cover in place.
